UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,251,608.

Specification of Letters Patent.

Patented Jan. 1, 1918.

Application filed September 16, 1914. Serial No. 861,966.

To all whom it may concern:

Be it known that I, CLIO B. YAW, a citizen of the United States, and resident of Arlington, in the county of Hudson and State of New Jersey, have invented certain new and useful Improvements in Type-Writing Machines, of which the following is a specification.

My present invention relates to tally strip mechanism for typewriting machines, and its general object is to provide improved mechanism of the character specified. More specifically stated, one object of my invention is to provide new and improved means for feeding the tally, another object is to provide new and improved means for inking the tally, and a further object is to provide improved paper feeding means coöperative with the platen.

20 To the above and other ends my invention consists in the features of construction, combinations of devices, and arrangements of parts hereinafter described and particularly pointed out in the claims.

25 In the accompanying drawings,

Figure 1 is a fragmentary front elevation of the upper portion of a No. 11 Remington typewriting machine embodying the preferred form of my invention.

30 Fig. 2 is a side elevation of Fig. 1, the line spacing handle and connections also being shown.

35 Fig. 3 is a horizontal sectional view taken on a plane indicated by the dotted line $x-x$ in Fig. 2 and looking downward.

Fig. 4 is a transverse sectional view taken on a plane indicated by the dotted line $y-y$, Fig. 3, and looking in the direction of the arrow.

40 Fig. 5 is a fragmentary sectional view taken longitudinally of the platen through its axis.

Fig. 6 is a fragmentary front elevation of the platen and associate parts showing the construction of the paper feeding devices that coöperate with the platen.

Fig. 7 is a transverse sectional view taken on a plane indicated by the dotted line $z-z$ in Fig. 6 and looking in the direction of the arrow.

Fig. 8 is an end view, partly in section, showing the disposition of the right-hand unit or group of the paper feeding devices shown in Fig. 6.

Fig. 9 is a detail perspective view of certain of the paper feeding devices shown in Figs. 6-8.

As appears from Figs. 1, 2 and 6, the main frame of the No. 11 Remington front-strike typewriting machines to one of which my invention is shown as applied comprises a top plate 1 from which rise lugs 2, said lugs providing supports for grooved guide rails 3 that coöperate through anti-friction balls 4 with a front bar 5 and rear bar 6 of a carriage truck, which further includes end bars 7 connecting said front and rear bars. Shiftably connected with said truck by devices 8 is a platen frame or carrier comprising end bars or plates 9 and cross rods or bars 10 and 11, said platen frame and its supporting truck constituting a traveling platen carriage. The end bars 9 provide bearings for a two-part shaft comprising stub ends or sections 12 and 13 on which is mounted a rotary platen 14. As appears from Fig. 5 the right-hand shaft or section 13 bears in a bushing 15 which is threaded into the end bar 9. The platen 14 comprises an ordinary wooden core 16 and rubber sheath 17. The mounting at the left-hand end is of ordinary construction. At the right-hand end the stub shaft 13 is secured in a platen head 18 which is fixed to the right-hand end of the core 16 by screws 19. The outer reduced end portion of the head 18 receives a line spacing ratchet wheel 20 which is secured to said head by screws 21. Mounted loosely on the platen head 18 and confined between the ratchet wheel 20 and the right-hand end of the platen is a second line spacing ratchet wheel 22 and a gear wheel, 23, the ratchet wheel 22 and gear wheel 23 being connected so that they will turn together as by devices comprising a pin 24. Coöperative with the ratchet wheel 20 is the usual spring mounted detent 25 and line spacing pawl 26, said pawl being loosely dependent from a stud 27 (Figs. 1 and 2) which is fixed to a supporting arm 28 loosely mounted on the bushing 15, the pawl having the usual limited motion on the arm 28. Said bushing also provides a support for a regulating arm 29, said arms 28 and 29 being confined loosely between the inner face of the end bar 9 and a nut 30 screwed on the inner end of the bushing 15, as appears from Fig. 5.

The pawl 26 is actuated by a train of devices illustrated in Fig. 2 and comprising a link 31 which connects said pawl with the longer arm of a bell crank 32 which is fulcrumed at 33 on the carriage truck, the short arm of said bell crank being connected by a link 34 with a crank arm 35 secured to the rear end of a rock shaft 36, said rock shaft extending forward and terminating in a downwardly projecting hand piece or arm 37. The rock shaft bears in a housing 38 fixed to the carriage truck and is provided with a restoring spring (not shown) which is contained within said housing. By operating the line spacing hand piece 37 in the usual way the train of devices connecting it with the pawl 26 is actuated and the pawl itself is caused to coöperate with the ratchet wheel 20 to turn the platen through a line space distance. In the present instance the regulating devices are set so that this operation communicates a unit of line space movement to the platen or a "single" space, as it is termed. This actuation of the pawl 26 also automatically actuates a supplementary pawl 39 which is rotatably mounted on the stud 27 to the left of the pawl 26 and in position to coöperate with the teeth of the ratchet wheel 22. Except under certain conditions, however, the pawl 39 is maintained in inoperative position in respect to the ratchet wheel 22 by a wire spring 40 which is coiled around the stud 27 between the pawls and engages at its ends with pins 41 and 42 projecting oppositely from said pawls. The tendency of said spring is constantly to throw or hold the pawl 39 forward away from the ratchet wheel 22, this forward movement of the pawl being limited by the engagement of the pin 42 with the forward end of a slot 43 formed in the pawl 26, in which slot said pin is adapted to play. In order to overcome the spring 40 and move the pawl 39 into operative position, that is, into position in which it may coöperate to turn the ratchet wheel 22 when the handle 37 is actuated, devices are provided which are brought into operation automatically to effect the desired result. Said devices comprise a bar 44 (Figs. 1-3) which is arranged forward of the platen and extends longitudinally thereof in position to engage with the front lower side of the pawl 39 during lengthwise movements of the carriage. The bar 44 terminates at its ends in forwardly inclined portions or cams 45. Said bar is rigid on a plate 46 formed with a slot 47 which receives at its ends headed screws 48 by which the member comprising the bar 44 and plate 46 is secured to the top plate 1. The construction is such that the device comprising the bar 44 and cams 45 is always stationary and in unvarying relationship with the top plate, the screws 48 coöoperating with the ends of

the slot 47 to prevent any endwise movement of the slotted plate 46 even when the screws are loosened. With the parts positioned as in the drawings, the pawl 39 will be inoperative but as the carriage moves leftward said pawl will engage with the right-hand cam 45 and will be forced rearward by said cam against the spring 40 until the said pawl is brought into engagement with the rear face of the bar 44 by which it will be maintained in position to operatively engage with its ratchet wheel during further leftward movements of the carriage until said pawl rides forward over the left-hand cam 45. The bar 44 is so positioned that during the time it is effective to engage said pawl the tally strip hereinafter described is opposite the printing point on the platen. After the pawl rides down over the left-hand cam it will become ineffective but during the return movements of the carriage said pawl will again ride up on to the bar 44 by reason of the action of the left-hand cam 45. It will be understood that the pawl 39 will always be effective so long as it is in engagement with the bar 44, but that at all other times it will be inoperative so that actuations of the line space handle 37 will not affect said pawl 39 so far as causing any action on the ratchet wheel 22 is concerned. Except for certain details the double pawl construction heretofore described is like that disclosed in the application of Arthur W. Smith filed Feb. 17th, 1914, Serial No. 819,258, and is not broadly claimed *per se* by me.

To coöperate with the platen 14 in the present instance, paper feeding devices of novel construction are provided which will be described in connection with Figs. 6-9. Said devices comprise a series or set of a number of units each composed of a main and secondary feed roller section and the mountings thereof, each unit being adapted to be adjusted into and out of working position without affecting the other units, which may be thrown off and released at will while the non-working unit remains at all times ineffective. The purpose of this construction is to throw out of use the unit which is opposite the tally strip so that the tally strip may pass around the platen without at any time being affected by the feeding devices that coöperate with said platen, and since the tally strip in the present instance is so mounted that it may be adjusted to various positions lengthwise of the platen, it is desirable that any one of the paper feeding devices may be adjustable to non-working position at pleasure. In the present instance there are three of these units and the description of one of them will be understood as applying to all. Each unit or group of paper feeding devices comprises a main feed roller section 49 and a sec-

ondary section 50, these being mounted respectively on rods or shafts 51 and 52 which are supported at their ends on parallel arms 53 pivoted at 54 between their ends to forwardly extending arms of three-armed lever members 55 which are pivotally mounted on a rod 56 that is rigid on the platen frame. Said rod 56 is secured to angular brackets 57 which are fixed by screws 58 to the bar 10 and extend rearward therefrom and then upward, at an angle, the rod 56 being supported at the angle. The downwardly extending arms of the three-armed lever members 55 are connected by draw springs 59 to the bar 10, the springs tending constantly to maintain the rollers 49 and 50 in cooperation with the platen as in Fig. 7. The upwardly extending portions of the brackets 57 are bored out to permit the passage there through of a release rock shaft 60 which bears at its ends in the platen frame and as provided near its left-hand end with the usual releasing arm or lever 61. The parts as thus far described are common to the No. 11 Remington machine.

Novel releasing devices are mounted on the shaft 60 comprising collars 62 arranged in pairs spaced apart, there being a pair of these collars for each paper feeding unit. Each collar is bored out, as indicated at 63, to fit over the rock shaft 60 and receives a pair of set screws 64 by which the collar may be adjustably secured in fixed relationship to said shaft. Between the said screws the collar is formed with a slot or kerf 65, and each collar further comprises an upright portion or abutment 66 that receives a set or adjusting screw 67 that is in register with or in the same vertical plane as the slot 65. Bearing rotatably on the shaft 60 and confined within the slot 65 is a releasing lever 68. The lower arm of each lever is adapted to cooperate with the upright arm of one of the three-armed lever members 55. The upper arm of the lever 68 passes in rear of the abutment 66 and is adapted to cooperate with the back face thereof, as in Fig. 7, or with the end of the set screw 67 when the latter is screwed in rearwardly through the abutment, as in Fig. 8. In the present instance the left-hand paper feeding unit and the middle paper feeding unit are arranged with the levers 68 normally set as in Fig. 7, while the right-hand unit, which is opposite the tally strip devices to be hereinafter described, has its levers 68 set as in Fig. 8. With the levers 68 normally set as in Fig. 7, an actuation or rearward push of the release lever 61 will rock the shaft 60 and cause the abutments 66, acting against the upper arms of the levers 68, to rock said levers, causing the lower arms of said levers to cooperate with their respective three-armed lever members 55, rocking said lever members on the rod 56 and causing the arms 53 to be lowered and the feed or pressure rollers carried thereby to be released. On the other hand, the screwing in of the adjusting screw 67 in the Fig. 8 position, causes said screws to act individually on their respective levers 68, rocking said levers on the shaft 60, which is stationary at the time, and causing the lower arms of said levers, acting against their respective three-armed levers 55, to overcome the springs 59 and effect the release of the associate feed or pressure rollers, as in Fig. 8. It will be understood that the throw-off of the pressure rollers as in Fig. 8 is a permanent one so long as the adjusting screw 67 remains screwed in, and this whether the release lever 61 is actuated or not. The only effect of the releasing action on the right-hand unit is to move the feed rolls comprised in it somewhat farther away from the platen than they appear in Fig. 8. It will be understood that the right-hand unit may be restored to effective relationship with the platen by unscrewing the screw 67 and permitting the upper arm of the lever 68 to be restored to engagement with the back of the abutment 66 under the influence of the springs 59 acting through the three-armed levers 55. It will be seen that the abutments 66 are in effect crank arms on the rock shaft 60, which are effective to engage with and move the levers 68 which are loose on said rock shaft; also that the screwing in of the screws 67 has the same effect as would a resetting of said crank arms toward the rear with a consequent change in the normal position of the levers 68, of which said crank arms are actuators; or, in another sense, couplers whereby the loose levers 68 are in effect caused to rock with the shaft 60 as though they were set or fixed thereon. It will be further noted that by the present invention there is provided a plurality of aligned, individual feed rolls that are selectively discardable at will, and that with these are combined means for casting off the non-discarded or active feed rolls, such casting off or releasing not interfering with the discarded roll or rolls. In the present case the discardable rolls are arranged in two lines or sets comprising independent parallel pairs of feed rolls. The discardable rolls are indefinitely held in disuse and the construction provides, as will hereinafter appear, for adjusting the tally carrier or roll lengthwise of the platen to bring it into register with a roll or rolls which may have been discarded or set in disuse.

The tally strip devices proper are mounted on two parallel rods or bars 69 and 70 arranged above the platen, one directly in front of the other and secured at their ends to the bars 9 (Figs. 1, 2, 3 and 6). The tally strip supporting frame comprises parallel upright end plates 71 and a connecting

cross bar 71^a. Said plates are forked at their lower ends, the forks being provided with hub portions 72 which fit over the rods 69 and 70, the hubs receiving set screws 5 by which the plates 71 are adjustably secured to said rods or bars. The construction permits the plates 71 and the devices carried thereby to be set at different places lengthwise of the platen. Near their tops 10 the plates 71 are off-set rearward and upward, their upper ends providing bearings for a tally delivery carrier, spool or holder comprising a hub 73, a flange 74 fixed at the left-hand end of said hub, and a projecting 15 pin or stub shaft 75 rigid with said hub and said flange. The pin is formed with a depression at its end which co-operates with the pointed end of a hand controlled spring pin 76 which bears in a housing 77 secured 20 to the left-hand plate 71 and extending laterally leftward therefrom. The right-hand end of the hub 73 is depressed to co-operate with a friction disk 78 which has a stem 79 that is adjustably fixed to the upper end of 25 the right-hand plate 71.

The tally strip 80 is wound into roll form on a paste board core 81, which is slipped on the spool hub 73 and frictionally engages therewith. The spring pin 76 forces the end 30 of the hub 73 against the friction disk 78 with sufficient pressure that a friction is exerted to retard upwinding movements of the tally strip and prevent excess advance thereof under a sudden pull or jerk. The free end 35 of the tally strip is drawn off of the back of the tally roll and over the cross rod 71^a, thence passing downward into the control of novel tally feeding devices which are arranged above the platen. Said devices comprise 40 three tally feed or pressure rollers arranged between the end plates 71. The central roller comprises a core 82 and a rubber sheath 83 (Fig. 6). The core 82 is slidably mounted on a shaft 84 which passes through 45 holes in the end plates 71 and extends the full length of the platen, bearing at its ends in journals formed in the end bars 9. The shaft 84 is provided with a longitudinal groove 85 which is engaged by tongues 82^a 50 turned or bent inward from the ends of the core 82. The construction is such that the pressure roller 82, 83 may be slid along the shaft 84 whenever a readjustment of the tally frame 71, 71^a takes place, while at the same time, 55 through the tongue and groove connections 85, 82^a the said roller is forced to turn whenever the shaft 84 receives rotary movements. Such movements may be communicated to the shaft by hand through a finger button 86 60 (Fig. 1) fixed to the right-hand end of said shaft outside the adjacent end bar 9. The shaft 84 and the central pressure roller may also be rotated automatically through connections between said shaft and the gear 5 wheel 23, said connections comprising a

pinion 87 provided with a hub 88 that fits over the shaft 84 to the left of the end bar 9, said hub receiving a set screw 89 by which the pinion 87 is fixed to the shaft. Between the pinion 87 and the gear wheel 23 is arranged an idler pinion 90 which constantly meshes with both said wheel and said pinion, said idler being rotatably mounted on the supporting rod 69, being confined loosely between collars 91 and 92 on said rod (Fig. 1). 75 Arranged at the rear of the central pressure roller 82, 83 and co-operative therewith is a second pressure roller comprising a core 93 and a rubber sheath 94, while forward of the central roller and also co-operative therewith 80 is a third pressure roller comprising a core 95 and a rubber sheath 96. These two outer pressure rollers are confined between the end plates 71, being rotatably mounted on rods or shafts 97. The rods bear loosely in 85 slots 98 formed horizontally in the end plates 71. Said slots are of such length that they may be moved outwardly, carrying the outer rollers with them far enough to cause said rollers to disengage from the central 90 pressure roller. Normally however the outer rollers are maintained in spring pressed engagement with said central roller by spring means comprising two wire springs 99 which are wound around the rod 69 and 95 have end portions which extend upward and hook over the end portions of the rods 97, said end portions projecting beyond the plates 71 (Figs. 1 and 2).

Means are provided for at will overcom- 100 ing the springs 99 and forcing the outer pressure rollers away from the central pres- 105 sure roller so as to render the tally feeding means inoperative. Said means comprise cam members fixed to the projecting ends 110 of the forward rod or shaft 97 (Figs. 1, 2 and 4). The right-hand cam member com- 115 prises an arm 100 having a hub 101 which fits over the rod 97 and is fixed thereto as by a set screw. The arm 100 curves rear- 120 ward over the shaft 84 and is provided at its rear with a curved or cam edge 102 which is adapted to co-operate with the projecting end of the rear rod 97. Said arm is further provided with an upward extension 100^a 115 from the end of which projects a lateral finger piece or key 103. When the finger piece 103 is pushed downward and rearward it causes the forward rod or shaft 97 to turn and brings the cam 102 into engagement 120 with the rear rod 97, said cam acting on said rod to force it rearward in its slotted bearing, while the re-action forces the forward rod 97 forward in its bearing. To insure a proper releasing action a similar 125 cam member is provided at the left comprising a curved arm 104 having a hub 104^a secured to the forward rod 97 and termi- 130 nating at its rear in a cam similar to the cam 102, the cam acting on the left-hand pro-

jecting end of the rear rod 97. The left-hand cam member 104 is not provided with a finger piece. As a preliminary to adjusting the tally strip 80 its outer pressure rollers are cast off from the central roller by manipulation of the key or finger piece 103, and then the tally strip is passed down between the central roller and the rear roller behind the platen and around the same, and up at its front side and thence between the central and front pressure rollers, after which the outer pressure rollers are restored to operative position. Thereafter the tally strip may be advanced at will by turning the finger button 86. Also it will be understood that when the tally strip is brought opposite the printing point the pawl 39 will have been moved to operative position so that an actuation of the line space handle or lever 37 will not only turn the platen through the pawl and ratchet devices 26 and 20 but will also operate automatically to turn the tally pressure rollers and feed the tally strip around the platen. This last result is accomplished by the pawl 39 acting on the ratchet wheel 22, causing it to turn the gear wheel 23 which through the idler 90 turns the pinion 87, causing a rotation of the shaft 84 and of the central pressure roller mounted thereon. The rotation of the central pressure roller is transmitted to the outer pressure rollers, causing the rear roller, in conjunction with the central roller, to draw the tally strip off the delivery holder and advance it downward toward the platen, while the coöperation of the front roller with the central roller simultaneously tends to draw the tally strip upward away from the platen at the front side thereof. It may be noted at this point that the operation of the line spacing handle 37 at this time is limited to one actuation since the space between the bar 44 and the teeth of the ratchet wheel 22 is so narrow that the pawl 39, after it has once been lifted by an actuating operation, is prevented from dropping downward to a position where it can engage a fresh tooth of this ratchet wheel. This construction is advantageous in that it safeguards against faulty operation of the mechanism and serves as an indication that the tally strip has been actuated. While the endwise relationship between the pawl and ratchet mechanism 39, 22 and gears 23 and 90 on the one hand and the platen on the other is a constant one, the endwise relationship between the platen and the central tally feed roller is variable, changing with the adjustment of said roller, which however is constantly connected with its ratchet 23.

The main work sheet 105 (Fig. 2) is arranged with its right-hand marginal portion overlying the tally strip, said sheet being fed around the platen by coöperation between the same and the feeding devices

comprising the pressure rollers 49 and 50, of which, it will be recalled, only the central and left-hand units are in operation in the present instance. The main work sheet 105 receives ink impressions from a ribbon 70 which is controlled by a vibratory carrier 106 (Fig. 2) of ordinary construction. It is preferable that the tally strip also should receive inked impressions as distinguished from carbon impressions, and to this end 75 supplementary inking devices of novel character for the tally strip are provided which will be described in connection with Figs. 1, 2 and 3. Said devices comprise two supplementary ribbon spools 107 arranged in 80 parallelism, one inside of each of the end plates 71, said spools being mounted loosely upon a shaft 108 which extends through openings in said plates 71. The spools are adapted to be connected in alternation to 85 rotate with the shaft 108 through hand controlled clutch devices, certain of said clutch devices serving also as bearings for the shaft 108, being interposed between said shaft and the supplementary ribbon spools, 90 of which in effect they are a part. At the left outside the end plates 71 a clutch wheel or member 109 is mounted co-axially with the shaft 108, said wheel being provided with crown clutch teeth 110 and having a 95 hub 111 which extends inward or toward the right through an opening in the plate 71 to the right of which plate is mounted the ribbon spool 107, said spool being fitted over the hub 111 and secured thereto by a 100 set screw 111a. The construction permits the clutch wheel 109 and the spool 107 to rotate as one while the plate 71, interposed between them, prevents movement of the clutch member and spool lengthwise of the 105 shaft 108. This shaft bears in the hub 111 which serves as a journal for it. The shaft may turn independently of the wheel 109 and its ribbon spool, which devices on the other hand may also turn independently of 110 the shaft. Coöoperative with the wheel 109 is a second clutch wheel 112 provided with crown clutch teeth 113 that are adapted to mesh with the teeth 110. The wheel 112 is suitably fixed to the shaft 108 near its left-hand end and is provided with a hub 112a formed with two circumferential grooves 114 and 115. Adapted to coöperate with these grooves is a pivoted latch 116 pivoted at 117 to the end of the cross rod 71a, and provided with a draw spring 118, which tends to force said latch downward about its pivot and maintain it engaged with one or another of the grooves 114 and 115, depending on which is in register therewith. When thus engaged, endwise movement of the shaft 108 is prevented, but when the latch is lifted the shaft 108 may be shifted 120 endwise to bring the clutch wheel 112 into engagement with the clutch wheel 109 or 125 130

to disengage it therefrom, while at the same time causing corresponding changes to take place in the clutch members associated with the right-hand spool 107 and now to be described. To facilitate endwise movement of the shaft it is provided at its ends with detachable knobs or finger pieces 119. A clutch wheel 120 is arranged at the right of the right-hand plate 71 and is provided with clutch teeth 121 and a hub 122 which extends inward through the plate 71 and surrounds the shaft 108. The right-hand spool 107 is fitted over the inner end portion of the hub 122 and is fixed thereto by a set screw 123. The shaft 108 and the wheel 120 are relatively rotatable and in order to connect them for simultaneous rotation a clutch device or wheel 124 is fixed to the shaft 108 near its right-hand end and is formed with inwardly projecting clutch teeth 125 adapted for co-operation with the teeth 121. The clutch wheels 112 and 124 are so arranged in respect to their associated clutch wheels that only one of said connecting clutch wheels 112 and 124 can be operative at a time. Thus when the wheel 112 is clutching the wheel 109 and so connecting the left-hand ribbon spool to turn with the shaft 108 the wheel 124 is inoperative and the right-hand ribbon spool is consequently loose on the shaft. If the latch or detent device 116 be lifted and the shaft 108 be moved endwise toward the left, the right-hand spool 107 will be clutched to the shaft by the wheel 124, while the left-hand spool will be freed by reason of the disconnection of the clutch wheel 112, thus reversing the direction of the ribbon feed. The shaft 108 is a ribbon driving or power shaft which is adapted to be turned automatically or by hand through connections to the shaft 84. Said connections comprise a pinion 126 which, as best appears from Fig. 6, has a slideable connection with the shaft 84 but is also compelled at all times to rotate with said shaft by reason of a radial pin 127 fixed to said pinion and engaging the groove 85, the construction being such that the pinion may be shifted endwise along the shaft while retaining its operative connection therewith. Said pinion meshes with a gear wheel 128 which surrounds and is fixed to the clutch wheel 124. Flanges or disks 129 fixed to the sides of the gear wheel 128 embrace or engage loosely with the sides of the pinion 126 and compel the pinion and gear wheel to remain constantly in mesh no matter what lateral shifting movements take place. For example, when the shaft 108 is moved endwise in either direction to reverse the ribbon, one or another of the flanges 129 will compel the pinion 126 to participate in this movement, the pinion sliding along its shaft 84. Said shaft, it will be recalled, receives rotary movement either from the finger piece 86 or from the train of connections that are actuated from the pawl and ratchet devices 39, 22. These rotary movements are communicated to whichever of the ribbon spools 107 is clutched to the shaft 108 at the time. For convenience of rapidly turning the spool by hand, the train of connections between the shaft 84 and the ratchet wheel 22 may be broken by moving said shaft endwise toward the left to disconnect the pinion 87 from the pinion 90. During this movement the shaft will slide through the pinion 126, which will retain its connection with the gear wheel 128 so that if thereafter the shaft 84 be rotated by the finger piece 86, said pinion will transmit motion through said gear to the ribbon spool shaft 108, which will be rotated to advance the ribbon, although the pawl and ratchet ribbon actuating devices remain inactive. The supplementary ribbon, indicated at 130, is of narrow width and is adapted to be wound on the spools 107, its ends being connected to said spools by spring hooks 131, said hooks partly encircling the hubs of the spools to which they are secured at one end by screws 132, the free ends of said hooks being pointed as indicated at 133 to facilitate the piercing of the end portions of the ribbon. Between the spools the ribbon is controlled by a guide plate 134 which is slotted as indicated at 135 to receive headed screws 136 by which said guide plate is adjustably secured to a pivot plate 137 that is provided with ears 138 formed with holes which fit over the shaft 108 between the ribbon spools. Thus the guide plate is pivotally supported on the ribbon spool shafts. Said guide plate is formed at its side edges just below and forward of the spools with guide slots 139 through which the ribbon passes in its downward course, and at its lower side the guide plate is formed with diagonal guide slots or turning bars 140 over which the ribbon passes and by which it is directed inward at right angles in a horizontal direction and so as to be opposite the printing line on the platen; this horizontal portion of the ribbon between the turning bars 140 being the printing portion thereof. The guide plate 134 between the turning bars and above the printing portion of the ribbon is cut away, as indicated at 141, leaving a large open space. It will be understood that when the parts are set as in Fig. 1, the left-hand ribbon spool will be turned to wind the ribbon thereon, the ribbon at the same time being drawn off the right-hand spool and the horizontal printing portion of the ribbon advancing toward the left from the right-hand turning bar to the left-hand turning bar. This printing portion of the ribbon is interposed between the work sheet 105 and the tally strip 80.

so that when the right-hand side of the main work sheet receives type impressions through the main ribbon controlled by the carrier 106, the tally strip will simultaneously receive imprints through the auxiliary ribbon 130. By reason of the pivotal mounting of the guide plate 134 it may be swung up to carry the auxiliary ribbon away from the platen and leave the front 10 or printing face thereof fully exposed. The upper edge of the plate 134 is beveled or sharpened, as indicated at 142, to provide a severing device for the tally strip which is led upward between the forward feeding 15 roll and the central feeding roll through the space or slotway formed between the shaft 108 and the back of the upper portion of the plate 134. Leaf springs 143 pivotally secured on the cross rod 71^a outside 20 the plate 71 extend forward and cooperate at their free ends with the outer flanges of the auxiliary ribbon spools, exerting sufficient pressure on said spools to prevent undue turning movements thereof, said leaf 25 springs thus serving as brakes.

With the parts constructed and arranged as described, when the tally strip is at the right of the printing point the main sheet only will receive type impressions, and an actuation of the line space handle will serve only to advance the main sheet, the tally strip and auxiliary or carriage carried ribbon feeding devices remaining unaffected. When, however, in the course of the leftward movement of the carriage the tally strip is brought opposite the printing point, an actuation of the usual printing instrumentalities will cause type impressions to be made on the main sheet and duplicated 30 on the tally strip, and when thereafter the line spacing handle 37 is operated, it will not only advance the main sheet a unit of line space distance but will automatically advance the tally strip to the same extent 35 and will simultaneously cause a feeding movement of the auxiliary ribbon.

The ribbon mechanism *per se* is not claimed herein as it is the subject of a divisional application Serial No. 102,643, filed 50 June 9, 1916.

Various changes may be made without departing from my invention.

What I claim as new and desire to secure by Letters Patent, is:—

55 1. In a typewriting machine, the combination of a platen carriage; a platen mounted thereon and adapted to receive a plurality of work sheets; sets of devices for advancing said work sheets, each set comprising a wheel, engaging members one for each of said wheels, and a single means for actuating said members; a device for preventing the operation of one of said members; and mechanism operating at predetermined 60 points in the traveling movements of said

carriage to render said preventive device inoperative, said means being restricted thereafter to a single actuation.

2. In a typewriting machine, the combination of a carriage; a platen thereon carrying a plurality of work sheets; means comprising line spacing ratchet wheels for advancing said work sheets, pawls cooperative with said ratchet wheels, and a single means for actuating said pawls; a device for preventing the operation of one of said pawls; and mechanism operating at a predetermined point in the carriage travel to render said device inoperative on its pawl, which pawl is thereafter capable of receiving a single actuation only from said means.

3. In a typewriting machine, the combination of a carriage; a platen thereon carrying a plurality of work sheets; means comprising line spacing ratchet wheels for advancing said work sheets, pawls cooperative with said ratchet wheels, and a single means for actuating said pawls; a spring tending constantly to throw one of said pawls away from its ratchet wheel and render it ineffective; and a stationary cam device for overcoming said spring during the carriage travel and moving the associate pawl to effective position, the relation between said cam device and the ratchet wheel with which said pawl cooperates being such as to prevent more than a single effective actuation of said pawl while it is within the control of said cam device.

4. In a typewriting machine, the combination of a carriage, a platen thereon carrying a plurality of work sheets, means comprising line spacing ratchet wheels for advancing said work sheets, pawls cooperative with said ratchet wheels, said pawls having a common pivot, spring means tending to throw said pawls away from each other, a lost motion connection between said pawls for limiting the effect of said spring means, and means cooperative at a predetermined point in the travel of the carriage with one of said pawls to overcome the effect of said spring means thereon.

5. In a typewriting machine, the combination of a carriage, a platen thereon carrying a plurality of work sheets, means comprising line spacing ratchet wheels for advancing said work sheets, pawls cooperative with said ratchet wheels and hung on a common pivot pin, a spring bearing on said pivot pin and cooperative with said pawls to throw them oppositely, a pin and slot connection between said pawls, means for actuating said pawls, and a stationary cam member cooperative with one of said pawls to overcome the effect of said spring thereon.

6. In a typewriting machine, the combination of a platen, a plurality of aligned, individually discardable feed rolls, and means for simultaneously casting off the active or

non-discarded rolls, the discarded feed roll or rolls being withdrawn from the control of said casting-off means as a result of such discarding.

5 7. In a typewriting machine, the combination of a platen, a plurality of aligned feed rolls, devices for simultaneously casting off or releasing said feed rolls, and means for holding in disuse one or more of said feed 10 rolls without interfering with the casting off or releasing of the remaining rolls, the feed roll or rolls held in disuse, being withdrawn as a result of being held out of use, from the control of the releasing devices.

15 8. In a typewriting machine, the combination of two lines or sets of feed rolls arranged in independent parallel pairs, releasing devices for said feed rolls, and means requiring the manual use of a tool distinct 20 from the machine for fixing in a position of disuse selected feed rolls and withdrawing such rolls from the effective control of said releasing devices.

25 9. In a typewriting machine, the combination of a plurality of feed rolls, key operated devices for simultaneously releasing said feed rolls, and means requiring the manual use of a tool distinct from the typewriting machine for setting indefinitely in 30 disuse any selected feed roll without interfering with the remaining feed rolls.

35 10. In a typewriting machine, the combination of a platen; a pressure roller co-operative therewith, means for releasing the same comprising a key controlled rock shaft, and a lever arm thereon; and means for adjusting said lever arm independently of said rock shaft to hold said pressure roller in released position.

40 11. In a typewriting machine, the combination of a platen; a pressure roller co-operative therewith; means for releasing the same comprising a key controlled rock shaft, a lever loosely mounted thereon, and a crank 45 arm fixed to said rock shaft and co-operative with said lever; and means mounted on said crank arm for adjusting said lever circumferentially of said rock shaft and independently of movement thereof.

50 12. In a typewriting machine, the combination of a pressure roller; means for releasing the same comprising a key controlled rock shaft, a lever loosely mounted thereon, and a crank arm fixed to said rock shaft and 55 co-operative with said lever; and a screw carried by said crank arm and effective on said lever to vary its relationship with said rock shaft.

60 13. In a typewriting machine, the combination of pressure rollers; spring pressed pressure roller frames or carriers; releasing means comprising a key controlled rock shaft, levers loosely mounted thereon and co-operative with said frames, and crank arms 65 fixed to said rock shaft; and means carried

by said crank arms and effective on said levers to vary their normal location.

14. In a typewriting machine, the combination of a pressure roller; a spring pressed carrier for said roller; means for releasing the same comprising a key controlled rock shaft, a crank arm fixed to said rock shaft, a lever loosely mounted on said rock shaft and embraced by said crank arm; and a screw on said crank arm and co-operative with one arm of said lever, the other arm of said lever being operative on said carrier.

15. In a typewriting machine, the combination of a platen, a set of pressure roll devices co-operative therewith, said set comprising a plurality of units, each unit including a pressure roller and a spring pressed carrier therefor, means effective on said frames to release said roller, said releasing means comprising a key controlled rock shaft, levers loosely mounted on said rock shaft and one at least co-operating with each unit, crank arms fixed to said rock shaft and co-operating with said levers, and screws carried by said crank arms and adjustable to vary the normal position of said levers.

16. In a typewriting machine, the combination of a carriage, a platen, a set of pressure roll devices co-operative therewith, said set comprising a plurality of units, a carriage carried tally holder adjustable lengthwise of the platen and opposite or in register with one or another of said units, and means for at will setting selected ones of said units independently of each other out of co-operative relationship with said platen.

17. In a typewriting machine, the combination of a carriage, a platen thereon provided with a plurality of work sheets, sets of devices for advancing the work sheets, a single means for actuating said sets, one of said sets being normally ineffective, ink ribbon mechanism for one of said work sheets, and means rendered operative by traveling movements of the carriage to render said single means effective on the normally inoperative set and also effective to actuate said ribbon mechanism.

18. In a typewriting machine, the combination of tally strip supporting devices, a carriage, a platen over which a tally strip or work sheet is fed, line spacing mechanism for advancing said tally strip or work sheet, ribbon mechanism for said tally strip or work sheet, and means rendered operative by traveling movements of the carriage for bringing said ribbon mechanism into control of said line spacing mechanism.

19. In a typewriting machine, the combination of a carriage, a platen provided with a work sheet or tally strip, devices for feeding the same, ribbon mechanism for said work sheet or tally strip, hand controlled actuating devices for said mechanism normally disconnected therefrom, and means

- brought into play during the carriage travel to render said devices effective on said ribbon mechanism.
20. In a typewriting machine, the combination of tally strip supporting devices, a carriage, a platen thereon, ribbon mechanism for the tally strip carried by said carriage, hand controlled actuating devices for said ribbon normally disconnected therefrom, and means brought into play by traveling movements of said carriage for rendering said devices effective on said ribbon mechanism.
21. In a typewriting machine, the combination of a carriage; tally strip supporting devices, the tally strip being adapted to receive type impressions from a ribbon that is carried by the carriage; means for advancing the tally strip ribbon, said means comprising a finger piece or key normally ineffective; and stationary means for rendering said finger piece effective, said means operating during traveling movements of the carriage.
22. In a typewriting machine, the combination of a carriage, a platen, tally strip devices on said carriage, ribbon mechanism for the tally strip, and means controlled by a single finger piece for advancing the tally strip and feeding the ribbon, said means comprising a device whereby said means are effective only when the tally strip is at or opposite the printing point.
23. In a typewriting machine, the combination of a platen, line spacing devices therefor comprising a finger piece, tally strip devices, ribbon mechanism for the tally strip, said finger piece in certain positions of the platen being ineffective to feed the tally strip and actuate the ribbon mechanism, and means for rendering said finger piece effective to feed the tally and actuate the ribbon mechanism in other positions of the platen.
24. In a typewriting machine, the combination of a carriage, a platen, tally strip devices, ribbon mechanism for the tally strip, devices for line spacing the platen comprising a finger piece, said line spacing devices being ineffective on the tally strip and the ribbon mechanism in certain positions of the carriage, and means for rendering said finger piece effective to feed the tally strip and actuate the ribbon mechanism when the carriage reaches a predetermined position in its travel.
25. In a typewriting machine, the combination of a platen, tally strip supporting devices, carriage carried ribbon devices operating with the tally strip, pawl and ratchet devices for turning said platen, pawl and ratchet devices for feeding said ribbon, and a single finger piece for actuating both sets of pawl and ratchet devices.
26. In a typewriting machine, the combination of a platen, tally strip supporting devices, carriage carried ribbon devices co-operating with the tally strip, pawl and ratchet devices for turning said platen, pawl and ratchet devices for feeding said ribbon and a single finger piece for actuating both sets of pawl and ratchet devices, said finger piece being inoperative to feed the ribbon when the platen is in certain positions.
27. In a typewriting machine, the combination of a carriage, a platen, tally strip supporting devices, carriage carried ribbon devices co-operating with the tally strip, ribbon mechanism, line spacing devices controlled by a single finger piece operative to turn the platen and feed the ribbon, connections between said ribbon mechanism and said finger piece including a shaft provided with a finger button, said shaft being movable endwise to break the connections between said mechanism and said finger piece, and said ribbon mechanism then being operative by said finger button independently of said line spacing devices.
28. In a typewriting machine, the combination of tally strip supporting devices, a carriage, a platen, carriage carried ribbon spools carrying a ribbon that co-operates with the tally strip, a shaft on which said spools are loosely mounted, clutch devices fixedly connected with said ribbon spools, and other clutch devices fixedly connected with said shaft, said shaft being movable endwise to render alternately operative the clutch devices thereon.
29. In a typewriting machine, the combination of tally strip supporting devices, a carriage, a platen, carriage carried ribbon spools carrying a ribbon that co-operates with the tally strip, a shaft on which said spools are loosely mounted, clutch devices fixedly connected with said ribbon spools, other clutch devices fixedly connected with said shaft, said shaft being movable endwise to render alternately operative the clutch devices thereon, and a spring pressed latch co-operative with grooves in said shaft to maintain it in adjusted positions.
30. In a typewriting machine, the combination of tally strip supporting devices; a carriage; a platen; carriage carried ribbon spools carrying a ribbon that co-operates with the tally strip; a shaft on which said spools are loosely mounted; clutch devices fixedly connected with said ribbon spools; other clutch devices fixedly connected with said shaft, said shaft being movable endwise to render alternately operative the clutch devices thereon; pawl and ratchet devices; and a train of gearing connecting said pawl and ratchet devices with said shaft, said train comprising a gear wheel fixed to said shaft, and a pinion slidable during ribbon reversing operations, said pinion remaining constantly in mesh with said gear wheel.

31. In a typewriting machine, the combination of tally strip supporting devices, a carriage, a platen, carriage carried ribbon spools carrying a ribbon that coöperates with the tally strip, a shaft on which said spools are loosely mounted, clutch devices, said shaft being movable endwise to alternately connect it with said spools through said clutch devices, and a train of hand actuated 10 gearing for turning said shaft, certain members of said train having an unvarying endwise relationship with said platen and certain other members being shiftable endwise of said platen when said shaft is shifted.

32. In a typewriting machine, the combination of a traveling platen, a tally strip holder carrying a tally strip which passes around the platen, a support for said holder adjustable lengthwise of the platen, a central 15 tally feeding roller adjustable with said support, a roller coöperative with said central roller to draw the tally from the holder, another roller coöperative with said central roller to draw the tally away from the 20 platen, pawl and ratchet devices having a constant relation endwise of said platen, and connections between said pawl and ratchet devices and said central roller, said connections remaining effective in the different 25 positions to which said central roller may be 30 adjusted.

33. In a typewriting machine, the combination of a carriage; a platen; a shaft on said carriage; tally strip feeding devices 35 comprising a roller on said shaft, said devices being adjustable lengthwise of said platen; and means for turning said shaft comprising pawl and ratchet devices, said pawl and ratchet devices having a constant 40 normal position for all of the different positions to which said tally feeding devices may be adjusted.

34. In a typewriting machine, the combination of a platen, a tally holder, a central 45 tally feed roller between said holder and said platen, a second feed roller coöperative with said central roller to draw the tally from the holder, a third feed roller coöperative with said central roller to draw the 50 tally from the platen, and hand controlled means comprising a single finger piece for simultaneously releasing said second and third feed rollers.

35. In a typewriting machine, the combination of a platen, a tally holder, a central 55 tally feed roller between said holder and said platen, a second feed roller coöperative with said central roller to draw the tally from the holder, a third feed roller coöperative with said central roller to draw the 60 tally from the platen, spring means for pressing said second and third feed rollers toward the central roller, and means comprising a single finger piece for overcoming 65 said spring means and throwing said second

and third rollers oppositely away from said central roller.

36. In tally feeding mechanism for typewriting machines, the combination of a central tally feed roller, a second feed roller 70 coöperative with said central roller to draw the tally from the tally holder, a third feed roller coöperative with said central roller to draw the tally from the platen, shafts on which said second and third feed rollers are 75 mounted, spring means operating on said shafts to press said second and third rollers against the platen, and releasing means coöperative with said shafts for overcoming said spring means and moving said shafts 80 away from each other, said releasing means being controlled by a single finger piece.

37. In a typewriting machine, the combination of a platen, a tally holder, a central 85 tally feed roller, a second feed roller coöperative with said central roller to draw the tally from the holder, a third feed roller coöperative with said central roller to draw the tally from the platen, shafts on which 90 said second and third feed rollers are mounted, spring means operating on said shafts to press said second and third rollers against the platen, and releasing means coöperative with said shafts for overcoming said spring 95 means and moving said shafts away from each other, said releasing means comprising hand controlled cam devices.

38. In a typewriting machine, the combination of a platen; a tally holder; a central 100 tally feed roller between said holder and said platen; a second feed roller coöperative with said central roller to draw the tally from the holder; a third feed roller coöperative with said central roller to draw the 105 tally from the platen; shafts on which said second and third feed rollers are mounted; spring means operating on said shafts and pressing said second and third rollers against the platen; and releasing means coöperative with said shafts for overcoming said 110 spring means and moving said shafts away from each other, said releasing means comprising a crank arm fixed to one shaft and provided with a finger piece for operating it and also with a cam operative on the other 115 shaft when said finger piece is actuated.

39. In tally feeding mechanism for typewriting machines, the combination of a central tally feed roller, a second feed roller 120 coöperative with said central roller to draw the tally from the tally holder, a third feed roller coöperative with said central roller to draw the tally from the platen, shafts on which said second and third feed rollers are mounted, spring means operating to press 125 said second and third rollers against the platen, and releasing means coöperative with said shafts for overcoming said spring means and moving said shafts away from each other, said releasing means comprising cam 130

arms fixed to one shaft and operating on the other shaft to overcome said spring means and force said second and third rollers away from each other.

5 40. In a typewriting machine, the combination of a support for a tally strip, ribbon spools carrying a ribbon that coöperates with the tally strip, ribbon feeding mechanism, and a ribbon guiding plate arranged

10 to guide the ribbon between said spools, said plate being provided with a paper severing device.

15 41. In a typewriting machine, the combination of a support for a tally strip, a carriage, carriage carried ribbon spools carrying a ribbon that coöperates with the tally strip, ribbon feeding mechanism, and a ribbon guiding plate pivotally supported on said carriage and provided with a paper cutting edge.

20 42. In a typewriting machine, the combination of a support for a tally strip, a carriage, parallel ribbon spools supported on said carriage, said spools carrying a ribbon that coöperates with the tally strip, ribbon feeding mechanism, and a guide plate pivotally supported between said spools and provided at its sides with turning bars, the upper edge of said guide plate being beveled to provide a paper severing device.

25 43. In a typewriting machine, the combination of a platen, a plurality of alined, in-

dividually mounted feed rolls, means for at will affording selective discarding of the feed rolls while the rolls not discarded remain in co-action with the platen, and means for simultaneously casting off the non-discarded rolls, the discarded feed roll or rolls being withdrawn as a result of such discarding from the control of the casting-off means.

30 44. In a typewriting machine, the combination of a platen, a plurality of alined feed rolls, means for casting off said feed rolls to release a work sheet controlled by them, means for holding in disuse one or more of said feed rolls without interfering with the casting off of the remaining rolls, and a tally carrier adjustable lengthwise of the platen to a position where the tally strip, led from the carrier and passing around the platen, will be opposite the feed roll or rolls in disuse so that the tally strip may be at all times manipulated independently of such roll or rolls.

35 45 Signed at the borough of Manhattan, city of New York, in the county of New York, and State of New York, this 15th day of September, A. D. 1914.
